CIRCUIT-CONTROLLING FINGER FOR ELECTRICALLY-OPERATED MUSIC-PLAYING APPARATUS.

1,112,658.

Specification of Letters Patent.

Patented Oct. 6, 1914.

Application filed November 4, 1912. Serial No. 729,253.

To all whom it may concern:

Be it known that I, WALTER C. REED, a citizen of the United States, residing at Dalton, in the county of Berkshire and State of Massachusetts, have invented new and useful Improvements in Circuit-Controlling Fingers for Electrically-Operated Music-Playing Apparatus, of which the following is a specification.

This invention relates to those parts of electrically-operated playing apparatus for pianos and analogous musical instruments which coöperate with a perforated music sheet to close the circuits through playing magnets according to the notes to be played, and is applicable more particularly to circuit-controlling devices of the general character shown and described in U. S. Letters Patent No. 753,809, granted March 1, 1904, on the application of Powers and Jewell, in which the circuit through each playing magnet includes a metallic wire which is normally held out of contact with a metallic contact bar by means of a pivotally-mounted finger supported by the music sheet but arranged to drop through each perforation therein which passes beneath it, thereby closing the corresponding circuit at the contact bar during intervals determined by the length of the perforations.

The present invention is intended to improve upon prior forms of the pivotally-mounted circuit-controlling finger above referred to in certain respects which will hereinafter appear, and is illustrated in the accompanying drawings, in which:

Figure 1 is a side view, partly in elevation and partly in section, of a circuit-controlling mechanism embodying my improvements as preferably constructed; Fig. 2 is a top plan view of the pivotally-mounted finger shown in Fig. 1; and Fig. 3 is an end view of the same as viewed from the right hand end of Fig. 1.

Referring to Fig. 1 of the drawings, 2 indicates a portion of a perforated music sheet of the usual character, 3 indicates one of the perforations therein, and 4 indicates the support over which the music sheet passes. My improved circuit-controlling finger, which is typical of the series of like fingers employed in a complete apparatus, is shown at 5 and is pivotally mounted at one end on a fixed rod 6 common to all the fingers. At its other

end the finger 5 is provided with the usual insulating block 7, and between its ends it has a downwardly-projecting point 8 which controls the position of the finger by resting upon the imperforate portions of the music sheet 2 as the latter passes beneath it, the finger being thus supported in elevated position except at the times when a perforation such as 3 passes beneath the point 8, whereupon the finger drops slightly as said point moves downward through the perforation into the usual groove 9 provided in the support 4. This movement completes the circuit through the corresponding playing magnet by means of the wire 10, one end of which is located in a recess in the insulating block 7 while at its other end it is connected to a fixed support 11 in such position that between its ends it passes over and adjacent to the usual contact bar 12, at its point of contact with which the playing magnet circuit is opened and closed.

As described thus far the parts are similar to those commonly employed in playing apparatus of this character, but in prior constructions the fingers have been provided with perforations to receive the rod on which they are pivotally mounted, and hence in order to remove any bent, broken or worn out finger and replace it by another finger it has been necessary to remove this rod from its supports and from all the fingers as well. This results in disassembling the entire series of fingers, inasmuch as they merely receive the contact wires loosely and are held in place by the rod only, and much time and trouble are involved in restoring the parts to their normal positions. According to my present invention this disadvantage is obviated by providing the pivotally-mounted end of the finger 5 with a slot 13 having at its inner end a circular periphery such as will form a bearing for the finger upon the rod 6, said slot extending upward and also slanting somewhat forward, or in the direction of movement of the music sheet 2, which is indicated by the arrow in Fig. 1. By this arrangement of the slot both the drag exerted on the finger 5 by the music sheet beneath it and the tendency to upward movement of the pivotally-mounted end of said finger, due to the action of the finger as a lever under the downward pressure of the wire 10 with the point 8 serving as the fulcrum,

cause the bearing at the end of the slot to press against the rod 6, and hence in operation the finger has no tendency to become disengaged from said rod 6, but on the contrary is kept in close contact therewith and its pivotal axis is maintained invariable. As another or additional means for preventing accidental displacement of the finger the slot 13 may be so shaped that at some point 10 between its inner and outer ends it has a width very slightly less (preferably about .003 of an inch less) than the diameter of said rod 6. The finger can be readily removed and replaced, however, without removing the rod 6 or disturbing any of the other fingers in any respect, by pressing the slotted end of the finger downward and backward until its slot is free from said rod, the terminal portion 14 of the finger being 20 sufficiently elastic to permit the rod to pass through the slightly contracted portion of the slot.

Another feature of my invention resides in the formation of the front edge 15 of the point 8 at such an angle with respect to the direction of movement of the music sheet beneath it that when the front end of a perforation 3 reaches the tip of the point 8 said point will not drop freely through the perforation, as heretofore, but its inclined front edge 15 will slide down the music sheet at the front end of the perforation until the wire 10 makes contact with the bar 12. The result of this arrangement is to lessen the noise 35 made by the falling of said wire 10 upon the contact bar, and since a number of these wires frequently fall at one time, by reason of the striking of chords, the noise made by the collective wires is very materially reduced. Moreover, when the wires such as 10 are allowed to drop freely upon the contact bar they frequently rebound and chatter, not only adding thereby to the noise produced but also impairing the firmness of the 40 contact which should be made between the wires and the contact bar, and this objection 45 also is avoided by my improvement.

It will be understood that the slant of the front edge of the point 8 is so calculated 50 with reference to the normal speed of the music sheet that the downward movement of the finger 5 will not be retarded sufficiently to materially interfere with the time values of the perforations 3, and although 55 this peculiar formation of the point 8 must necessarily delay slightly the contact at the bar 2, if it is to perform its intended function, the delay thus caused need not exceed a negligible fraction of a second or have any 60 more harmful effect than results from chattering at the contact bar, as such chattering itself delays the establishment of the full current strength in the playing magnet circuit.

65 Inasmuch as the angle of the front edge

of the point 8 is calculated to accord with the normal speed of the music sheet, it will be evident that when the speed of the sheet is varied to change the tempo of a composition, the downward movement of the finger 70 5 will be retarded to an increased extent if the speed of the music sheet is lessened and will be accelerated as the speed of the music sheet is increased, and the speed may conceivably be increased until the front end of 75 a perforation 3 will move away from the point 8 so fast that the sliding contact between said point and the music sheet will be broken. In such case, however, the finger 5 will merely drop freely and operate like 80 prior fingers of this type, whereas if the speed of the music sheet is reduced the delayed downward movement of the finger will not be important, because the time values of the perforations will be increased to a 85 much greater extent than the delay in the downward movement of the finger.

An incidental advantage gained by shaping the point 8 as above described is found in the fact that a blunter angle may be 90 formed at the tip of the point than is permissible in prior fingers, and hence less trouble is experienced on account of breakage of these points when they are hardened, it being the practice to give the points an 95 extreme degree of hardness in order that their sharp tips may not be worn down by long-continued use. It should also be mentioned that my improved contact finger is particularly adapted for use with music 100 sheets made of sheet metal, since the above-described operation of the point 8 requires its slanted front edge to be firmly supported by the material of which the music sheet is made.

The circuit-controlling finger illustrated in the accompanying drawing has its pivotal axis located substantially in a straight line coinciding with the direction of movement of the music sheet where the latter passes 110 the lower extremity of the point 8, but this feature is not claimed herein, being described and claimed in a co-pending application filed June 3, 1911, Serial No. 631,053.

105 I claim as my invention:

1. A circuit-controlling finger for electrically-operated music playing apparatus, said finger having a projection terminating in a point for controlling the movements of the finger, and a slot extending inward from one edge of the finger and terminating within the latter in a pivotal bearing to receive a supporting rod.

115 2. A circuit-controlling finger for electrically-operated music playing apparatus, 120 said finger having a projection terminating in a point for controlling the movements of the finger, and a slot extending inward from one edge of the finger and terminating within the latter in a pivotal bearing to receive 130

a supporting rod, said slot having a slightly contracted portion between the bearing and the open end of the slot.

3. A circuit-controlling mechanism for 5 electrically-operated music playing apparatus, comprising a finger having a projection terminating in a point for controlling the movements of the finger, said finger being provided with a pivotal bearing adapted 10 to receive a transversely-extending rod and with a slot leading from said bearing to one edge of the finger, and a make-and-break device controlled by said finger.

4. A circuit-controlling mechanism for 15 electrically-operated music playing apparatus, comprising a contact bar, a contact wire extending across the same, adjacent thereto, a supporting rod, and a finger pivotally mounted at one end upon said rod and 20 connected at its other end to the contact wire, said finger being provided with a projection terminating in a point for controlling the movements of the finger and with a slot leading from said rod to one edge of the 25 finger.

5. A circuit-controlling mechanism for electrically-operated music playing apparatus, comprising a pivotally-mounted finger having a point adapted to rest upon a

music sheet and pass through perforations 30 therein, the front edge of said point being formed at such an angle with respect to the directions of movement of the finger and the music sheet as to cause the point to slide down the sheet at the front end of a perforation, and a make-and-break device operated 35 by the pivotal movements of the finger.

6. A circuit-controlling mechanism for electrically-operated music playing apparatus, comprising a contact bar, a contact 40 wire extending across the same, adjacent thereto, and a pivotally-mounted finger controlling the movements of said contact wire and provided with a point adapted to rest upon a music sheet and pass through perforations 45 therein, the front edge of said point being formed at such an angle with respect to the directions of movement of the finger and the music sheet as to cause the point to slide down the sheet at the front 50 end of a perforation.

In testimony whereof, I have hereunto subscribed my name this first day of November, 1912.

WALTER C. REED.
